THERMOSTATIC PILOT VALVE MECHANISM

Noel B. Green, Cleveland, Ohio, assignor to The
Titan Valve and Manufacturing Co., Cleveland,
Ohio, a corporation of Ohio

Application August 17, 1939, Serial No. 290,549

1 Claim. (Cl. 158—117.1)

This invention relates to thermostatic pilot valve mechanism such as is used for controlling the flow of gas to the burner of a domestic hot water heater or like devices.

The object of the invention is to provide improved valve mechanism of this kind which not only is wholly safe in that the safety pilot thermostat shuts off the supply of gas to both the pilot and main burners in case of emergency operation, but the mechanism for the purpose is of simple and improved form, self-contained in that all parts are combined as a single unit, and which avoids the use of diaphragm valves or other devices which complicate the mechanism.

A further object is to provide improved valve mechanism of this kind adapted for installation indiscriminately in those systems where the hot water thermostat is either ahead of or behind the pilot thermostat.

A further object of the invention is to provide mechanism of this kind including a starting valve by means of which the gas may be temporarily supplied for heating the parts to a temperature in which the pilot supply is maintained.

Further objects of the invention are in part obvious and in part will appear more in detail hereinafter.

In the drawing, which represents one suitable embodiment of the invention,

Fig. 1 is an elevation, partly in section on the line 1—1, Fig. 4, showing the valve mechanism applied to a burner;

Fig. 2 is a detail sectional plan view, from beneath, on the line 2—2, Fig. 1, and showing the starting valve open and the maintaining and main burner valves closed;

Fig. 3 is a similar view illustrating the starting valve closed and the maintaining and main burner valves open; and

Fig. 4 is an elevation from the left in Fig. 1.

The thermostatic valve mechanism shown in the drawing comprises a hollow body or casing 1 provided with a connection 2 to which a gas supply pipe 3 for supplying the main burner may be connected, and also with a connection 4 for an outlet pipe 6 communicating with the main burner 7, which may be assumed to be used for heating water in a domestic hot water storage tank not shown.

Attached to the casing is a pilot burner, shown as comprising a tube 8 provided intermediate its ends with a small orifice 9 just ahead of the lateral air supply ports 10, the mixture of gas and air being led to a burner member 11 having an end port 12 for projecting a flame to or near the

main burner, and also a slot or other opening, such as one or more ports 13 for producing flames playing upon and heating the thermostatic elements, which include the usual expandible tube 14, made of brass, copper or the like, and the non-expandible rod 15, made of porcelain, steel or the like.

The supply of gas for the pilot flame is led to the tube 8 through a lateral passage 16 from a channel 17 in the main casting, the flow to which is either through a passage 18 to be later referred to, or through an opening within the valve seat 19 controlled by a valve 20 normally held to its seat by a compression spring 21. Valve 20 is the starting valve. It is normally closed, as shown in Fig. 3. To open it the operator applies his finger to the button 22, depressing the same against the effect of the spring 23, and the inner end of the stem 24, to which the button is connected, engages the valve member 20 and pushes the same off its seat to the position shown in Fig. 2, thereby establishing communication through the valve passage to the channel 17 from a supply channel 25 communicating with a chamber 26 and also with a lateral connection 27 to which a pipe may be connected for supplying gas to the starting valve and thence to the pilot burner. The pipe attached to the connection 27 may come from any source. If it comes from the main gas supply pipe the connection is taken off therefrom at a point ahead, or on the supply side, of any thermostatic valve subject to water temperature so that a permanent gas supply is provided for the pilot burner irrespective of other accessories.

The gas supplied to the inlet connection 2 is led to a chamber 28 in the valve body on the supply side of the main burner valve 29, which is biased toward its seat by a compression spring 29a but may be moved away from its seat by the effect of the thermostatic elements 14, 15 through any suitable mechanical connections. The drawing shows the rod 15 extending into the discharge outlet 30 where said rod is provided with a member 31 bearing against one face at one end of a lever 32, an intermediate portion of said lever resting against an abutment 33 forming a fulcrum for said lever, and the opposite end 34 of the lever lying opposite an extension 35 of the main burner valve 29. If the thermostatic elements are heated tube 14 expands and moves rod 15 to the right in Fig. 1, turning the lever 32 about its perch on abutment 33 and applying its end 34 to the main burner valve to move said valve from the closed position shown in Fig. 2

to the open position shown in Fig. 3, permitting gas to flow from the supply pipe 3 to pipe 6 and thence to the main burner. This valve will remain open so long as the thermostatic elements 14, 15 are heated to the proper temperature. The critical temperature to which the thermostat is responsive may be varied by removing a cap 40 from the valve casing to expose the end of a rod 41, extending into the casing and upon a threaded portion of which the perch 33 is mounted.

Axially aligned with the main burner valve 29 is a maintaining valve 42, biased toward its seat by a compression spring 43. Normally said valve is upon its seat, in the position shown in Fig. 2. Therefore gas supplied to the connection 27 flows through chamber 26 to passage 25 and may be permitted to flow to the pilot burner by opening the starting valve. Beyond the maintaining valve 42 is a channel 44 sealed from the chamber 28 by a flexible diaphragm 45, but communicating with the passage 17 on the discharge side of the starting valve 20.

The mechanism described operates as follows:

Let us assume all parts cold with any hand valve controlling main burner 7 open. Flow of gas to the main burner is prevented because the main burner valve 29 is closed, and to the pilot burner is prevented because the maintaining valve 42 and starting valve 20 are closed. The operator depresses the button 22, opening starting valve 20. Thereupon gas flows from the connection 27 by way of passage 25, through the open starting valve 20 to passage 17 and thence to the pilot burner. The pilot flame is ignited. Immediately the thermostatic elements 14, 15 are heated. Tube 14 expands, moves rod 15 to the right, applies lever 32 to the main burner valve 29, and opens the same. Thereupon gas flows from the supply pipe 3 through the main burner valve to pipe 6 and thence to the main burner 7, provided all other hand or controlling valves are open and heat is desired. The main burner therefore ignites.

As soon as the thermostatic elements 14, 15 are heated, the operator can remove his hand from the button 22, permitting the starting valve 20 to close. But by this time the valve 42 is open, because the effect of the lever 32 upon valve 29, opening the latter valve, is communicated to the valve 42 through the diaphragm 45. In other words, the stem of valve 29, when said valve is opened, pushes the diaphragm over to the left in Fig. 2 against a pilot 46 connected to valve 42 and opens the latter valve, holding it open so long as the main valve 29 is open. Opening of valve 42 permits a maintaining supply of gas to flow from the connection 27 to chamber 44 and thence to passage 18, bypassing the starting valve 20 and flowing to channel 17 and thence to the pilot valve. The latter will hence remain in operation so long as the flame burns and keeps the thermostatic elements hot.

If the flames all go out and the parts cool abnormally, the thermostatic tube 14 contracts, moves rod 15 to the left, swings lever 32 about its pivot and permits the springs 29a and 43, respectively, to close the main burner valve 29 and the maintaining valve 42, thereby cutting off all flow of gas to both the main burner and the pilot burner and requiring the apparatus to be again restored to operative condition by the same series of operations before described.

All parts of the mechanism are contained within the form part of the single unit, readily adaptable to any control system for gas burners. Of course, where any accessory control device, such as a hot water thermostat, is connected in the piping system beyond or on the outlet side of this valve mechanism, the maintaining supply of gas for the pilot flame obviously could come directly from the main burner supply stream through valve 29, dispensing with valve 42. But I find it preferable to construct this mechanism with such a maintaining valve and with a separate connection 27 for supplying gas for the pilot burner in order to adapt the mechanism to other systems, such as those where a hot water thermostat or the like is connected in the system ahead of the pilot valve mechanism.

Other advantages of the invention will be apparent to those skilled in the art.

What I claim is:

In the combination of a heating device, a fuel supply line therefor, and a pilot for said device, thermostatic control mechanism comprising a single casing providing two aligned chambers and a third chamber disposed at one side thereof, one of said aligned chambers housing a main burner supply valve controlling flow in said fuel supply line, a pilot maintaining valve in the other of said aligned chambers, said valves having aligned valve stems, the stem of said main valve being arranged to abut and open said maintaining valve when said main valve is opened, means preventing fuel leakage between said aligned chambers, a thermostat heated by said pilot, an operative connection between said thermostat and said main valve for causing opening of said main valve when said thermostat is hot and for causing closing of said main valve when said thermostat is cold, a normally closed manually controlled pilot starting valve in said third chamber, a fuel supply to said pilot maintaining valve chamber on the upstream side of said maintaining valve, there being a passageway in said casing communicating between the upstream sides of said maintaining valve and said starting valve, there being a passageway in said casing communicating between the downstream sides of said maintaining valve and said starting valve, and there being a passageway leading to said pilot from the downstream side of said starting valve.
